UNITED STATES PATENT OFFICE.

GEORGE WASHINGTON ASHLOCK, JR., OF OAKLAND, CALIFORNIA.

PROTECTIVE DEVICE FOR ELECTRIC SWITCHBOARDS.

Application filed June 25, 1923. Serial No. 647,514.

My invention is a protective device for electric switch boards.

My invention is illustrated in the accompanying drawing which forms a part of this specification and the appended claim.

Referring to the drawing:

Figure 1 is a sectional view of my invention and a switch board to which my invention is applied, taken on line 1—1 of Figure 2.

Figure 2 is a front elevation of my invention.

Figure 3 is a detail sectional view of the base, showing how the studs are mounted in the base.

In the drawing, 1 indicates a switch board, including a base 2 of insulation, and a knife switch 3 and a fuse 4 mounted on said base.

An arm 5 is secured to a bar 6 of insulation which connects the swinging ends of

the switch blades 7. Studs 10 projecting forwardly from the base 1, extend through the base and screw into bars 11 secured to the back of the base. A front plate 12 is riveted on the forward ends of the studs

10 in front of the switchboard. Braces 13 mounted on the lower studs 10 and resting against base 1, extend upwardly and forwardly against the plate 12, and the forward end of the upper studs 10 extend through

the upper forward ends of the braces, thus bracing the forward ends of the upper studs and providing a rigid mount for the plate 12. An operating lever 15 is fulcrumed in front of plate 12 in a bearing 16 on the front of said plate. A link 17 extends

through a vertical slot 18 in plate 12 and connects the arm 5 and lever 15. A door 20 is provided in the plate 12 in front of fuse

4 to permit access to the fuse, the door being hinged at its upper edge. A lug 21

extending from the front of the door 20

at the upper edge thereof is engaged by a cam 22 on the lower end of lever 15 to hold the door 20 closed when the lever is in switch closing position and the switch 3 is closed as shown in Fig. 1, thus preventing access to the fuse while the switch is closed. Upon pulling the upper end of the lever 15 outward, the switch 3, through link 17 and arm 5 is opened, and the cam 22 disengages the lug 21. The door 20 may then be opened for access to the fuse 4, the switch at this time being open. Upon swinging the lever inwardly and closing the switch the cam 22 engages the lug 21, if the door is open, and closes the door.

The plate 12 and lever 15 being mounted in front of the switch board and insulated therefrom by base 2 and bar 6, prevent one from touching the switch board and receiving an electric shock.

Having described my invention, I claim:

In combination with an electric switch board, a plate, means for supporting said plate spaced from the switch board, a member extending forwardly of said plate, an operating lever pivoted in said member, said plate having an opening to provide access to the switch board, a door hinged at its upper edge covering said opening, a lug attached to said door near its upper edge, a cam formed on the lower end of said lever and adapted to engage said lug, and a link pivoted at one end to said lever, extending through said plate and having its other end operatively connected to an electric switch on said switch board, said link, lever, lug and cam coacting to prevent the opening of the door when the switch is closed.

In testimony whereof I affix my signature.

GEORGE WASHINGTON ASHLOCK, Jr.
